(57) **CLAIM**

An ornamental design for a vane anemometer, substantially as shown and described.

DESCRIPTION

FIG. 1 is a front view of a preferred embodiment of this invention of a vane anemometer;

FIG. 2 is a back view of the preferred embodiment of FIG. 1;

FIG. 3 is a left side view of the preferred embodiment of FIG. 1;

FIG. 4 is a right side view of the preferred embodiment of FIG. 1;

FIG. 5 is a top end view of the preferred embodiment of FIG. 1;

FIG. 6 is a bottom end view of the preferred embodiment of FIG. 1;

FIG. 7 is an isometric view of the preferred embodiment of FIG. 1 with the impeller cover closed; and,

FIG. 8 is an isometric view of the preferred embodiment of FIG. 1 with the impeller cover open.

Any broken lines in the drawings are in the views for illustrative purposes only and form no part of the claimed design.

1 Claim, 5 Drawing Sheets
